LOOSE LEAF BINDER

Paul O. Unger, Elmhurst, Ill., assignor to Wilson-Jones Company, Chicago, Ill., a corporation of Massachusetts

Application August 27, 1936, Serial No. 98,121

4 Claims. (Cl. 129—17)

This invention relates to loose leaf binders and more particularly to prong binders.

It is an object of this invention to provide a loose leaf binder which will permit the sheets 5 to lie perfectly flat when the binder is opened. It is a further object of this invention to provide simple and efficient means for holding the binder in closed position that may be readily released to permit opening of the binder. Other 10 objects of this invention will become apparent upon reading the following description, taken in conjunction with the accompanying drawings, in which

Figure 1 is a perspective view of the loose 15 leaf binder in open position with the sheets removed.

Figure 2 is a cross sectional view of the binder in closed position.

Figure 3 is a longitudinal sectional view taken 20 along the line III—III of Figure 2; and

Figure 4 is a top plan view of the binder with portions broken away to facilitate illustration of the structure.

In the drawings, the reference numeral 2 indicates a back member to each longitudinal edge 25 of which a strip 3 is hingedly connected. Each strip 3 has a cover member 4 hinged along its outer longitudinal edge. The hinges are so arranged that the back member, the strips 3 and 30 the cover members all lie in the same plane when the binder is open.

A prong carrying plate 5 is rigidly secured to each strip 3. The plate has a plurality of curved sheet retaining prongs 6 secured thereto in any 35 suitable manner. The sheet retaining prongs are spaced off center so that no rights or lefts are required in assembling the binder and the prongs on opposite sides of the binder will not engage each other when the binder is closed. 40 Each prong carrying plate is provided with a flange 7 at each end. The flanges 7 each have a projection 8, an aperture 9 in said projection, and a shoulder 10, all for a purpose to be hereinafter described.

The back member 2 has a flat plate member 11 secured thereto in any suitable manner. The ends of the plate 11 are bent upwardly, as indicated at 12 and 13 to help form a shallow compartment 14. The end 12 is recessed, as indicated at 15, for a purpose hereinafter described. A pair of flat plates 16 are secured to the plate 11 and extend longitudinally thereof to form the side walls of the shallow compartment 14. The 55 top wall of the compartment 14 comprises a flat

plate 17 secured to the plates 16 and the ends 12, 13 of the plate 11.

The plates 11 and 17 are provided with a plurality of registering apertures 18 and 19 adjacent each end of the plates. The apertures 18 and 19 are so positioned that when the binder is closed the projections 8 pass through the apertures 19 and into the apertures 18. In this position the shoulders 10 engage a locking bar 20 adjacent one end of the apertures 19.

The locking bar 20 is slidably mounted in the compartment 14. The bar 20 is slightly bowed at its center, as indicated at 21, providing sufficient friction to prevent the bar from sliding too freely. The bar is provided with a projection 22 adapted to engage a pair of apertures 23 and 24 to help hold the bar in either locking or inoperative position. A member 25 provided with a pair of tongues 26 is rigidly secured to one end of the bar 20. If desired the member 25 could be made integral with the bar. The member 25 is sufficiently wide that the inner edges of the plates 16 act as guide rails to prevent lateral movement of the locking bar. A pair of tongues 27 similar to the tongues 26 is provided on a member 28 rigidly secured to the bar 20 at its opposite end. The member 28 is bent upwardly, as indicated at 29, to form a finger pull 10 to facilitate manipulation of the locking bar.

The tongues 26 and 27 each project in the same direction and are adapted to pass into and out of the apertures 9 to lock the binder or to permit it to be opened. The movement of the bar in one direction is limited by the engagement of the finger pull 29 with the end of the plate 35 17. The plate 17 is provided with a depending projection 30 adapted to engage the inner edge of the member 25 to limit the movement of the locking bar in the opposite direction.

The operation of the binder is quite simple. 40 When the binder is in open position the prongs are spaced apart and a plurality of sheets 31 may be impaled upon the prongs. When the binder is closed the finger piece 29 is pushed inwardly to lock the prongs in the position shown 45 in Figure 2. An outward pull on the finger piece releases each of the apertures 9 from the tongues 26, 27 and permits movement of the binder to open position. As can be seen from the illustration of Figure 1, the sheets will lie perfectly 50 flat when the binder is in open position, and they may be manipulated with ease.

While I have described a single embodiment of my invention in detail, it will be understood that the description is illustrative, rather than 55

restrictive, as many details may be modified or changed without departing from the spirit or scope of my invention. Accordingly, I do not desire to be restricted to the exact construction 5 described, except as limited by the appended claims.

I claim:

1. In a loose leaf binder, a back member, a shallow compartment parallel to said back member, a pair of prong carrying plates hingedly mounted adjacent opposite edges of said back member, a projection on each of said prong plates adapted to pass into said compartment when the binder is in closed position, and means in said 10 compartment adapted to cooperate with said projections to hold said binder in closed position.
2. In a loose leaf binder, a back member, a pair of superimposed plates secured to said back member, said plates having a plurality of registering 15 apertures, a prong plate provided with a projection at each end, said projections being adapted to enter said apertures when the binder is closed, and means positioned between said superimposed

plates adapted to engage said projections to hold said binder in closed position.

3. In a loose leaf binder, a back member, a pair of superimposed plates secured to said back member, said plates having a plurality of registering apertures, a prong plate provided with 5 projections adapted to enter said apertures when the binder is closed, said projections each having an aperture positioned between said superimposed plates, and a locking bar having a plurality of fingers adapted to engage said last mentioned apertures to hold said binder in closed position.

4. In a loose leaf binder, a back member, a shallow compartment parallel to said back member, a pair of prong carrying plates hingedly mounted adjacent opposite edges of said back member, a projection on each of said prong plates adapted to pass into said compartment when the binder is in closed position, and a locking 10 bar in said compartment, said locking bar being slidable longitudinally to cooperate with said projections to hold said binder in closed position.

PAUL O. UNGER.
